ELASTIC FABRIC

Richard Hesse, Melrose, Mass., assignor to Everlastik, Incorporated, Chelsea, Mass., a corporation of Massachusetts

Application July 14, 1937, Serial No. 153,571

2 Claims. (Cl. 139—421)

The invention relates to an improvement in elastic fabrics.

The object of the invention is to provide a very open weave elastic fabric which makes it adaptable for various uses including shoe gorings, hosiery top webs, ladies' underwear and sanitary belt webs, corset materials, men's underwear webs, and garter, suspender and belt webs.

As will later be explained, the open weave effect is primarily obtained through the employment of a leno construction. Attempts have been made to employ a leno construction for analogous purpose for obtaining the open effect in the weave, but unsuccessfully, owing to the fact that the elastic warp strands were laterally displaceable or would slide sidewise leaving large and unsightly openings. The essential object of the invention is to obviate this difficulty.

The invention can best be seen and understood by reference to the drawing in which

Fig. 1 is a plan of an elastic fabric embodying the invention, and,

Fig. 2 is a side elevation of one of the weft threads.

Referring to the drawing

1, 2, etc. represent sets of elastic warp strands representative of those which form the body of the woven fabric. These strands are wound or covered elastic strands like those commonly employed in an elastic woven fabric. Of these strands the strands 1 in each set are plain standard warps, while strands 2 are leno warps, inasmuch as they cross alternately back and forth over 1 in the weaving of the fabric, the crossings of 2 over 1 being at points 3 and 4, 3 representing the point crossing from left to right, and 4 the return crossing from right to left. Between these points of crossing the strands 1 and 2 of each set of warps are bound by sets of picks of weft, or filling, to lie spaced, paralleling one another and imparting to the warps 1 by reason of their elasticity, a form much like the leno warps 2, although the warps 1 are, in point of fact, plain warps.

In addition to the sets of warps 1 and 2 the fabric is also preferably provided with supplemental edging, or border warps 5, these warps being plain standard warps engaged by the sets of picks of weft, or filling, to lie in spaced position paralleling one another.

The sets of picks of weft, or filling, which cross the warp strands 1 and 2 between the points 3 and 4 of their crossing, and which also cross the edging warps 5, are in one or any plural number of picks but preferably three in number, 6, 7 and 8, re-

spectively. These picks of weft, or filling, are inelastic wefts of a specially spun type which impart to the thread a knotted and curled appearance and this by providing the body or core of the thread with knotty sinuous surface excrescences relatively large as compared with the body, and very rough. In other words, surface smoothness is avoided and a superficial thickness of thread obtained. The more common type of this kind of thread is known in the trade as "boucle".

In following the passage of the picks of weft across the fabric the picks of weft 6 and 8 pass under the warps 1 and over the leno warps 2, while the picks of weft 7 pass over the warps 1 and under the leno warps 2. Thus woven all the picks of weft pass between the warps 1 and 2 in the part thereof which lie between the points 3 and 4 of their crossing, thus spreading the warps and increasing the size of the openings 9 left between the sets of warps 1 and 2 at the points 3 and 4 of their crossing by which the fabric is made an open fabric.

The picks of weft are also woven progressively through the border warps 5, some of the picks of weft passing around the outermost ones of these warps.

An elastic fabric thus formed possesses peculiarly desirable properties in accordance with the objects of the invention. In a fabric of this kind there is no difficulty with slippage of the picks of weft along the warps in a longitudinal direction. The crossing of the leno warp over the warp 1 prevents this. In the present fabric there is, also, no sliding of the warps along the filling, or weft, threads in a sidewise direction owing to the character of the weft threads. This overcomes a difficulty heretofore inherent in a structure of this kind, which was aggravated if relatively large weft threads were employed and they were necessarily employed in order to separate as widely as possible the warp strands in the leno construction for obtaining the desired openings in the fabric. The difficulty with large threads in aggravating lateral slippage is that large threads will pass over the warp strands and have less frictional contact therewith than would smaller threads which have longer bearing against the warp strands at the points where the weft threads are interwoven. In the present construction relatively small weft threads are employed in comparison with the size of the warp strands, that is, the bodies of the weft threads are relatively small, which permits the weft threads to twine around the warp strands at the points of interweaving and have relatively long 55

friction contact therewith. At the same time the weft threads, provided as they are with knotty sinuous surface excrescences, increase the frictional resistance between these threads and the 5 warp strands, and give a superficial thickness to the weft threads, thus enabling them to separate the warp strands sufficiently to get the desired effect of relatively large openings.

The woven structure is also such, owing especially to the character of its weft threads, or filling, that finishing of the fabric has little or no effect on closing the openings in the fabric, a difficulty heretofore encountered.

I claim:

15 1. A woven elastic fabric comprising elastic warp strands with sets of said warp strands combining to form leno constructions, and picks of weft crossing said warp strands and interwoven therewith, said picks of weft consisting of threads 20 the bodies of which are small relative to the size of the warp strands whereby they may entwine around the warp strands and have relatively long friction bearing against the same at the points of interweaving, and which bodies of 25 the weft threads are provided with knotty sinuous surface excrescences whereby the frictional resistance between the wefts and warp strands

will be increased, and whereby, also, the said excrescences will impart a superficial thickness to the weft threads and enable them to better separate the warp strands for obtaining relatively large openings in the fabric.

2. A woven elastic fabric comprising elastic warp strands combined in sets, each set including a leno forming warp strand crossed alternately back and forth over a companion warp strand, and picks of weft crossing said warp strands and 10 interwoven therewith between the points of crossing of the warp strands, said picks of weft consisting of threads the bodies of which are small relative to the size of the warp strands whereby they may entwine around the warp strands and 15 have relatively long friction bearing against the same at the points of interweaving, and which bodies of the weft threads are provided with knotty sinuous surface excrescences whereby the frictional resistance between the wefts and warp 20 strands will be increased, and whereby, also, the said excrescences will impart a superficial thickness to the weft threads and enable them to better separate the warp strands for obtaining relatively large openings in the fabric.

RICHARD HESSE.
